UNITED STATES PATENT OFFICE.

ABRAHAM NOVICK, OF FLUSHING, NEW YORK, ASSIGNOR TO F. L. SMITH MACHINE COMPANY, INCORPORATED, OF NEW YORK, N. Y., A CORPORATION OF NEW YORK.

BLANK-LOCATING MECHANISM.

Application filed January 28, 1924. Serial No. 688,953.

To all whom it may concern:

Be it known that I, ABRAHAM Novick, a citizen of the United States, and a resident of Flushing, county of Queens, and 5 State of New York, have invented certain new and useful Improvements in Blank-Locating Mechanisms, of which the following is a specification.

This invention relates to means for aligning and centering blanks, particularly envelope blanks in envelope making machines and the like, and holding them in centered position until they are engaged by subsequent operating mechanism.

15 In the preferred form of embodiment of the invention, the aligning and centering of the blanks is accomplished by a pair of jogging fingers, which fingers are given an orbital movement, the operating stroke of 20 which is in the plane of the blanks and the return stroke of which is out of the plane of the blanks so that during this return stroke a new blank may be inserted 25 into position for being acted upon by the jogger. A distinct saving of time is thus made and the machine is rendered capable of a high speed of operation.

In accordance with a further feature of 30 the invention, the jogging fingers are arranged to move in converging planes so that the operation of the jogging fingers causes not only alignment of the blank but centering thereof as well. This feature is of particular importance for blanks which are relatively long and therefore difficult to 35 center.

According to still another feature of the invention, mechanism is provided for impressing on the joggers movement which is 40 translational as distinguished from rotational, so that adjustment of the mechanism for blanks of different sizes may be made without disturbing the orbital movement of the jogging fingers.

45 Various other features and advantages, included within the objects of the invention, will appear as the description of the invention proceeds.

Certain features disclosed but not claimed 50 herein are disclosed and claimed in my pending application, Serial No. 673,049, for bottom folding mechanism, filed November 6, 1923, and in my pending application, Serial No. 631,576, for mechanical movement, filed April 12, 1923.

Referring now to the drawings which illustrate a preferred form of embodiment of the invention, together with such parts of the envelope making machine as are necessary to illustrate the operation of the same, 60

Figure 1 is a side view of the mechanism;

Figure 2 is a rear view thereof;

Figures 3 and 4 are diagrammatic plan views illustrating the operation of the jogging mechanism; and 65

Figure 5 is a detail sectional view on the line 5—5 of Figure 1.

In the embodiment illustrated, the envelope blanks 1, comprising side flaps 1^a and bottom flap 1^b, are fed into the machine 70 by an endless belt 2 which travels over a pulley 4 at each end and under the forming blades 3. A shaft 4^a is provided for the pulley 4 and an idler or take-up roller 5 keeps the belt taut. The blanks coming 75 into the machine are passed between the positive feed rollers 6 and 7 and travel forward on the belt 2 under the weighted friction rollers 8, which frictionally hold the 80 blanks upon the belt so that they travel forward therewith, but permit them to be centered relative to the forming blades 3 85 and the folding mechanism.

At the lower end of the forming blades 3, the blanks contact with stops 9 which 90 are mounted on a bar 9^a which constitutes a part of the lower flap folding mechanism described in my co-pending application Serial No. 673,049, filed November 6, 1923. The position of stops 9 on bar 9^a is rendered 95 adjustable by means of screw 10 co-operating with a series of threaded holes 11 in the bar 9^a so that the various sizes of blanks may be accommodated.

As the blank is brought to rest against the stops 9, it is centered and brought into proper alignment by the action of the jogger fingers 12, so that the blank may then be accurately folded into the desired shape 100 or subjected to other operations necessary for forming the desired envelope.

Each jogging finger 12 is provided with an operating or tip member 13 adjustably mounted upon the end of the finger 12 by means of a telescoping tube 13^a which is held in position by a set screw 13^b. Each finger 12 is bent into a right angle 12^a and the end opposite the member 13 is mounted 105 for longitudinal and angular adjustment in a holder 14 which is provided with a set 110

screw 14^a and a key 14^b for loosening or tightening the screw 14^a when the finger is to be adjusted.

The holder 14 is carried on the end of 5 a slide 15 which passes through a guide or housing 16 provided with a cover plate 16^a, and is provided with a roller 17 at the end opposite the holder, for cooperation with a cam surface to be described later. 10 Projecting from one side of the housing 16 is another housing or guide 18, with a cover plate 18^a, for the slide 19 which carries a finger 20 projecting into a slot 21 in the slide 15. The other end of the slide 15 15 is provided with an oval shaped slot 22 for receiving one end of the flattened rod 23, the other end of which is received in a similar slot 22^a in the slide 19^a of the other half of the jogger. 20 The guides 16 and 18 are rigidly mounted upon a stationary part 24 of the machine, upon which is also mounted the rod 25 carrying the lever 26 for operating the rod 23 and slides 19 and 19^a. The lever 26 comprises a hub portion 26^a, which turns upon the rod 25, an arm 26^b connected with the rod 23, and an arm 26^c, carrying the cam roller 27 for cooperating with the cam 28. A spring 29 holds the roller 27 in contact 30 with the cam at all times.

A cam shaft 30 carries the cam 28, the cam members 31 and 32, and other cams for operating the various parts of the machine in properly timed relation.

35 The operation of the jogger is as follows:

At the initial position illustrated in Figure 1, the tip members 13 of the jogging fingers, are approximately in the position 40 illustrated in Figure 3. When the rollers 17, which are held in contact with the cams 31 and 32 by the springs 33, travel to the low side 31^a of the cams 31 and 32, the fingers 13, which are then in the plane of the blank, are 45 drawn downward in converging planes Z (Figure 2), which intersect the angle between the top and side flaps of the envelope blank. The blanks are thus aligned against stops 9 and because of the converging component of the downward movement are simultaneously centered laterally. The latter feature is of particular importance when the blanks which are subjected to the aligning operation are relatively long, as will be 50 readily understood.

In Figure 1, the movement of the jogging fingers is illustrated by the diagram "A", the direction of movement being illustrated by the arrows. It will be observed during 60 the downward movement described above, the tips of the jogging fingers are in the plane of the blanks. At the end of this movement the fingers are withdrawn from this plane, this withdrawal being brought about by cam 28, the low side of which at

this time passes under roller 27 of lever 26, thus permitting spring 29 to turn the lever clockwise in Figure 1 so as to draw out the slide 19 and draw the slide 15 toward the bottom 16^b of the guide 16. At the 70 completion of this movement the tips 13 are to the rear of the plane of the blanks, and while in this position, they are returned to the upper part of their stroke by the action of roller 17 which now passes 75 over the high side 31^b of cams 31 and 32. Because of the fact that the jogging fingers during the entire period of their return movement are behind the plane of the blanks, the blank previously aligned may 80 be withdrawn from its position against stops 9 (this withdrawal being effected by mechanism indicated at 9^b in Figure 1, the construction of which, however, need not be considered for the present purpose) and a 85 new blank may be inserted into position for alignment so that considerable economy of time and therefore rapidity of operation, may be realized. At the end of the upward movement, the jogging fingers are again 90 caused by cam 28 to move forwardly into the plane of the blanks, whereupon the entire cycle of operation is repeated.

It may be observed here that the length of the slot 21 is greater than that of finger 20 of 95 slide 19, so as to permit the slide 15 to move longitudinally with reference to slide 19, and the slots 22 in slide 19 are longer than the flattened sides of rod 23 to permit relative sidewise movement of the rod in the 100 slots.

105 It is to be noted that the adjustment of the fingers 12 by sliding them in and out of the holder 14 or by turning the holder relative to the slide 15, does not disturb or change the orbit A through which the joggers travel, as that is determined by the path of movement of the holder 14 on the end of slide 15, which path is unaffected by the adjustment. While the path traveled by the points 13 has 110 been referred to as an orbit, the movement of the points 13 is not one of rotation but one of translation and comprises four components, namely, downward, rearward, upward and forward, and all the movement is in a plane substantially as indicated at Z in Figure 2, the downward movement being in the plane of the envelope blank and the upward movement being in the rear of this plane.

115 While the movement of the jogger under the influence of the high and low points of the cam has been described, it is to be understood that the shape and position of the cams and the shape of orbit A as illustrated and described, is not intended to be mathematically correct, but is largely diagrammatic for the purpose of illustration.

120 In compliance with the patent statutes, I have described my invention in connection with one form of embodiment thereof,

but it is to be understood that the invention is not limited to the form of embodiment disclosed, but that various changes may be made therefrom without departing from the spirit of the invention or the scope of the accompanying claims.

What I claim is:

1. A device for jogging and centering blanks at rest against aligning stops, including jogging fingers moving in an orbital path into and out of the plane of the blanks.

2. A device for jogging and centering blanks at rest against aligning stops, including jogging fingers, and means for moving said fingers through a jogging stroke in the plane of the blanks and through a return stroke out of the plane of blanks.

3. In combination, aligning stops, means for intermittently feeding blanks against said stops into position to be jogged and means for jogging said blanks, said last-mentioned means being arranged to withdraw the joggers from the plane of the blanks at the beginning of their return movement to permit a new blank to be fed into position for being jogged.

4. In a mechanism of the character described, aligning stops, means for intermittently feeding blanks against said stops into position to be jogged, a jogging mechanism for said blanks, said mechanism being arranged to have its return movement clear of the plane of said blanks, and means for effecting said return movement of the jogger while a new blank is being fed into position.

5. In a device for jogging and centering blanks, the combination of jogging fingers, means for moving the fingers in the plane of the blanks to jog and center the blanks, said means being arranged to bring said fingers to rest at the end of the jogging operation, and means for withdrawing the fingers from the plane of the blanks in the last-mentioned position of the joggers and for returning the fingers to the plane of blanks at another position of the joggers.

6. In combination, a device for jogging and centering blanks, including jogging fingers adapted to move in an orbital path, and means for operating said fingers, said means comprising means to move the fingers downward in the plane of the blanks to align the same, means to move the fingers out of the plane of the blanks, means to move them upward, and means to move them into the plane of the blank to complete the orbit.

7. In combination, a device for jogging and centering blanks, including jogging fingers adapted to move in an orbital path, and means for operating said fingers, said means comprising means to move the fingers downward in the plane of the blanks to align

the same, means to move the fingers out of the plane of the blanks, means to move them upward, and means to move them into the plane of the blank to complete the orbit, and means to move the fingers through a path out of the plane of the blanks and return the same to jogging position.

8. The process of jogging and centering blanks which comprises jogging a blank on the operating stroke of the joggers, withdrawing the joggers from the plane of the blanks, and returning the same to the high point of their movement, and feeding another blank into jogging position during the return movement of the joggers.

9. The process of jogging and centering blanks which comprises jogging a blank on the operating stroke of the joggers, withdrawing the jogger from the plane of the blanks, and returning the same to the high point of their movement, and feeding another blank into jogging position during the return movement of the joggers, and returning the joggers to the plane of the blanks in position to jog the blank fed.

10. In a machine for jogging envelope blanks, the combination of a stop mechanism for one edge of the blanks, a pair of jogging fingers, means to operate the jogging fingers to jog the blanks against said stop mechanism, said means comprising mechanism for moving the fingers towards the blanks and convergingly toward each other to center the blank simultaneously in a longitudinal and sidewise direction.

11. In a machine for jogging envelope blanks, the combination of a means to feed the blanks into position to be jogged, means to stop the blanks, means to jog the blanks against said stops, means to withdraw the jogging means from the plane of the blanks at the completion of their jogging movement, and means to return said jogging means into jogging position, said feeding means operating during the return movement of the joggers to feed a new blank into position to be jogged.

12. In a machine for jogging envelope blanks or the like, the combination of a pair of jogging fingers, holders for the fingers and means to move the holders in orbital paths to impart corresponding movements to the fingers in planes which pass substantially through the angles formed by the end and side flaps of the envelope blanks.

13. In a machine for jogging envelope blanks or the like, the combination of a pair of jogging fingers, holders for the fingers and means to move the holders in orbital paths to impart corresponding movements to the fingers in planes which pass substantially through the angles formed by the end and side flaps of the envelope blanks, said movements of the holders being trans-

lational, so that the fingers in the holders may be adjusted to jog different size blanks without disturbing the orbit.

14. The combination with a pair of jogging fingers of means for moving said fingers in orbital paths, said means being arranged to cause translational movement of said fingers to the exclusion of rotational movement so as to permit of adjustment 5 in position of the fingers with reference to the said moving means without disturbing the path of movement of said fingers.

15. The combination with a stop mechanism of a pair of jogging fingers movable 10 toward and from said stop mechanism for cooperating therewith and means for moving said fingers through converging paths during their jogging operation.

16. In an envelope making machine, the 20 combination with a stop mechanism for the envelope blanks of a pair of jogging fingers and means for moving said fingers through orbital paths into and out of the plane of the envelope blanks, said paths being in intersecting planes.

17. In combination, conveying mechanism, frictional means for holding blanks on the conveying means so as to permit centering of said blanks, a stop mechanism for arresting the movement of the blanks, and jogging mechanism for centering the blanks against said stop mechanism, said jogging mechanism comprising a plurality of jogging fingers movable in orbital paths, said

movements being in the plane of the paper 35 during the jogging operation and out of the plane of the paper during the return operation, said jogging operations being at an angle to the line of side folds so as to effect simultaneously longitudinal and lateral 40 alignment of the blanks, means for operating said jogging fingers, said means being arranged to cause translational movement of the fingers to the exclusion of rotational movement thereof so as to permit of adjustments 45 of the fingers with reference to the moving means without disturbing the path of movement of the fingers.

18. In combination a jogging finger, a carrier therefor, means for moving the carrier in an orbital path to carry the jogger forward in the plane of the blank, withdraw it from said plane and retract it while clear of said plane, and means for adjusting the position of the jogger finger on the carrier to change the location but not the 50 operation of the finger, to adapt the machine for blanks of different sizes.

19. In an envelope making machine, the combination with an end stop, of jogger 60 mechanism comprising combined side and end jogging fingers, and means for moving said jogging fingers toward the end stop and toward one another to correctly position the blank longitudinally and laterally.

In testimony whereof I have affixed my signature to this specification.

ABRAHAM NOVICK.
